[57] CLAIM

The ornamental design for a magnetic tape cassette, as shown and described.

DESCRIPTION

FIG. 1 is a top perspective view of a magnetic tape cassette, showing our new design;

FIG. 2 is a bottom perspective view thereof;

FIG. 3 is a top perspective view thereof, with the cassette in an open position;

FIG. 4 is a bottom plan view with the cassette in a closed position;

FIG. 5 is a top plan view thereof;

FIG. 6 is a front elevation thereof;

FIG. 7 is a rear elevation thereof;

FIG. 8 is an elevation as seen from the left of FIG. 4;

FIG. 9 is an elevation as seen from the right of FIG. 4;

FIG. 10 is a bottom plan view with the cassette in an open position;

FIG. 11 is a top plan view thereof;

FIG. 12 is a front elevation thereof;

FIG. 13 is a rear elevation thereof;

FIG. 14 is an elevation as seen from the left of FIG. 10; and

FIG. 15 is an elevation as seen from the right of FIG. 10.
